TANK CAB

Conrad C. C. Burkhardt, Philadelphia, Pa.

Application July 26, 1930, Serial No. 470,974

17 Claims. (Cl. 105—360)

One object of my invention is to make a cast steel tank car as an integral casting of steel or of some light weight alloy, using a minimum number of parts yet maintaining all the requisite resistance to pulling, buffing and twisting strains.

Another object of the invention is to lower the center of gravity of the tank car in order to increase its stability and reduce to a minimum the possibility of its being overturned by tilting or by side swash of its contents.

Another object of the invention is to construct the tank car so as to dispense with the separate under-framing and the necessity for the anchorage of the tank to the frame.

And a still further object of the invention is to make the lower portion of the tank, and the dome section, as integrally cast units and thus avoid expensive flanging and press work.

In the accompanying drawings,—

Fig. 1 is a side view of an improved steel tank car illustrating the invention;

Fig. 2 is a longitudinal sectional view;

Fig. 3 is a plan view, partly in section on the line 3—3, Fig. 2;

Fig. 4 is a sectional view on the line 4—4, Fig. 2;

Fig. 5 is a sectional view on the line 5—5, Fig. 2;

Fig. 6 is a view of a modification showing the upper end sections welded to the lower cast frame.

The body 1 of the tank car is made as a single casting. This body portion extends to the line x—x through the center of the cylindrical portion of the car forming portions of the side members of the car, but the cast metal ends 2 extend the full height of the car as shown in Fig. 2. At each side of the body portion are flanges 3 reinforced by brackets 4 located at intervals throughout the length of the car, and the upper portion of the car is secured to the flanges. The lower portion of the body 1 of the car consists in the present instance of a semi-cylindrical outer shell 5 which is extended to form sides 5a and a transverse inner bottom plate 6 extending from side to side of the shell, and which is connected to the bottom of the shell by vertical webs 7, which extend the full length of the car and form a truss member of the car, which takes the place of the underframe of the car. The vertical webs extend to the ends 2 of the car body and in the present instance extend upwards to a point near the upper edges of the ends and act to reinforce the ends and particularly that portion of each end above the upper edges of the side portions of the body as clearly shown in Fig. 2. The webs are perforated at intervals as at 8 to lighten the structure and to allow the liquid in the car to

enter the space under the bottom plate. The bottom plate is curved upwards at each end as at 6a and has a series of perforations 9 therein to allow the liquid to enter all portions of the interior of the car body. The curved inner bottom plate extends to a point near the top of the end sections and aids to reinforce said end sections. The end sections, which project above the sides of the lower section conform to the particular contour of the upper section to which it is attached.

The casting is enlarged at each end so as to form a bumper structure 10 in which is the recess 11 for the draw bar of the coupling. This bumper construction extends preferably to the car bolster 12, which is cast integral with the body and has a pivot pin opening 13 for the pivot of the truck, the wheels of which are shown by dotted lines. 14 are transverse partitions, one on each side of the center of the car, and in these partitions are holes 14a. The partitions 14 break the longitudinal swash of the liquid in the car, while the vertical webs break the lateral swash of the liquid in the bottom of the car.

The central section of the upper portion of the car is made as an integral casting and consists of the segmental shell 15, which has a lower longitudinal flange 16 at each side and end flanges 17, which are riveted or otherwise secured to the flanges of the other parts of the car, the flanges 16 being secured by bolts or rivets to the longitudinal flanges 3 of the lower portion of the car, while the end flanges 17 are secured to the flanges 18 on the segmental sheet metal sections 19 of the upper section. These sheet metal sections are flanged at 20 and are secured to the longitudinal flanges 3 of the lower section, while the ends are secured by angle plates 21, which are attached to the end plates 2 of the lower casting. The dome 22 is cast integral with the section 15 of the upper portion of the car and may be made in any manner desired without departing from the essential features of the invention. The openings in the bottom section, as well as the openings in the vertical webs and the transverse partitions 14 are preferably of sufficient diameter to allow access of a man from the manhole in the dome to do cleaning or inspection at all parts of the interior of the tank when completed.

The casting may include the ordinary parts of a tank car, such as the push pole sockets, draft gear pockets, and lugs, brake mast step, grab irons, side bearings, center plates, side steps and side running boards, brake cylinder supports, brake lever fulcrums, brake lever supports, and

running board brackets, and the car may be made either of cast steel or if found desirable and expedient, it may be made of an aluminum alloy to reduce weight.

5 While I have shown the car in Fig. 5 as of cylindrical shape in cross section, it may be made in other shapes, such as that shown in Fig. 6, in which the lower section 5a has vertical sides and is flat on the underside. In this instance the 10 upper sections 19a are welded to the vertical sides of the lower section.

I claim:

1. The combination in a tank car having upper and lower portions, the lower portion being made 15 as an integral casting and consisting of an outer shell, an inner bottom plate, vertical webs extending the full length of the car and connecting the bottom plate to the shell; said parts forming part of the under frame for the car; end members 20 cast integrally with the lower portion; a central cast metal upper section, connected to the lower portion; and sheet metal upper side sections secured to the sides and ends of the lower portion and to the central upper section.

25 2. The combination in a tank car, of a lower cast metal section forming the under frame of the car; a central cast metal upper section secured to the lower section and having a dome; and sheet metal upper sections secured to and extending 30 from the cast metal upper section to the ends of the car and secured to said lower section and said ends.

35 3. The combination in a tank car, of a cast metal lower section consisting of a semi-cylindrical outer shell and a bottom plate, the said outer shell extending to a point about midway of the height of the car and having flanges; end members cast integrally with the lower section, three upper semi-cylindrical sections, comprising two 40 end sections and a central section, the central semi-cylindrical section having a dome and being made as an integral section, said central section having longitudinal flanges and end flanges, the said end sections being secured to the end flanges 45 of the central section and extending to the end of the car, the end sections also having flanges; means for securing the flanges of the three upper sections to the flanges of the lower section of the car; and means for securing the upper end sections to the end members of the lower section.

45 4. The combination in a tank car, of a lower section made in a single casting, including an outer shell and inner bottom plate; vertical connecting webs connecting the shell and the plate, and end members, the bottom plate being curved upward at each end to form reinforcements for the end members.

50 5. The combination in a tank car, of upper and lower sections, the lower section consisting of an outer shell, a bottom plate and vertical webs extending the full length of the car; end members extending above the sides of the shell, the bottom plate extending upward at each end, forming reinforcements for the end members, and the said lower section being made as an integral casting; and upper sections secured to the lower section, to the ends and to one another.

55 6. The combination in a tank car having upper and lower sections, the lower section being made as an integral casting and having an outer shell, a bottom plate; two vertical webs extending the full length of the car and extending from the bottom plate to the shell; end members; transverse partitions above the bottom and bumpers at each

end of the lower section; a central upper section made as an integral casting and having an integral dome; and separate upper sections extending from the cast metal upper section to the end members of the lower section, and said upper sections being secured together and to the lower section and end members.

5 7. A lower integral section for a tank car made of cast metal, consisting of an outer shell; an inner bottom plate; end members; vertical webs 10 extending longitudinally of the car and connecting the shell, the inner bottom plate and the end members, said end members extending above the inner bottom plate, the inner bottom plate and the webs having manholes opening therein, which 15 allow the content of the car to flow into spaces under the inner bottom plate; and upper sections secured together and to the lower section and the end members.

8. In a railway vehicle underframe, an arcuate 20 plate forming a tank bottom member for a cylindrical tank, and tank end members cast integrally with the said plate and extending above the side portions of the arcuate plate; and a longitudinal web vertically arranged, said web being integral 25 with the tank bottom and tank end members, the web extending upwards at each end where it joins the end members to reinforce said tank ends.

9. In a railway vehicle underframe, spaced bolsters, a longitudinal member of arcuate cross section between said bolsters and below the tops thereof and forming the bottom of a cylindrical tank, and end members extending upwardly above the tops of the side portions of the longitudinal 35 arcuate member; and two vertical webs located 40 one on each side of the center of the vehicle and extending longitudinally the entire length of the vehicle and integral with the end members, the webs adjacent the end members extending approximately the full height of said end members 45 while a portion of the web between said ends has a relatively shallow depth compared to the depth of the web adjacent said end members.

10. In a railway vehicle underframe, spaced 45 bolsters; an arcuate portion extending between 50 said bolsters and forming the main longitudinal member of the underframe and forming a tank bottom member; tank end members extending above the upper edges of the sides of the arcuate longitudinal member of the underframe; and vertical webs extending longitudinally of the underframe and connected integrally with the tank 55 end members and said arcuate longitudinal member, said longitudinal webs at each end extending to a point near the upper ends of the end members and acting to reinforce said end members.

11. In a railway vehicle underframe, spaced 60 bolsters; an arcuate section extending between said bolsters and forming the main longitudinal member of the underframe, said bolsters and arcuate section cooperating to form a tank bottom; a tank end member integral with said arcuate section and extending above the upper edges of the side portions of said arcuate section; a vertical web extending the entire length of the tank 65 and a portion of the web at the end member extending approximately the full height thereof while the body portion of the web has a relatively shallow depth compared to the depth of the web adjacent said end member, the whole being 70 formed as an integral casting.

12. A tank car, the lower portion of which is a single casting forming the outer shell and which includes the bottom of the car and portions of each side; an inner bottom plate above the 75

bottom of the shell which extends to and reinforces the said sides of the shell; and vertical webs extending from the inner bottom plate to the bottom of the shell and also extending longitudinally of the car.

13. The combination in a tank car of a lower portion made in a single casting and consisting of a semi-cylindrical shell and having end members extending above the upper edges of the side portions of the shell, three upper sections comprising two end sections and a central section all secured together and to the shell, each upper end section being also secured to its adjacent end member of the shell.

14. The combination in a tank car of a lower portion made in a single casting and consisting of a semi-cylindrical shell forming the sides and bottom of the car, said sides extending about midway of the height of the car and end members and transverse intermediate partitions integral with the shell, said end members and the partitions extending the full height of the car and upper sections secured together and to the sides of the shell, the end upper sections being secured to the end members of the shell.

15. The combination in a tank car of a lower cast-metal section consisting of a semi-cylindrical shell forming the bottom of the car and por-

tions of the sides thereof and integral end members extending above the upper edges of the side portions of the shell; a separate central cast metal upper section located at the center of the car and secured to the sides of the lower section, said central upper section having an integral dome; and separate upper end sections connecting the central upper section with the end members of the shell, and connected to the lower section.

16. The combination in a tank car, the lower portion of which is in a single casting which includes an outer shell forming the bottom and part of each side of the car and ends integral with the shell, said ends extending above the upper edges of the sides; and an upper section completely enclosing the upper portion and secured to the sides and ends of the shell.

17. The combination in a tank car, of a longitudinal plate arcuate in cross section and forming the bottom member for a cylindrical tank; tank end members cast integrally with the said plate and extending above the longitudinal edges of the arcuate plate; and an upper section secured to the end members and to the longitudinal edges of the arcuate bottom member.

CONRAD C. C. BURKHARDT.
